UNITED STATES PATENT OFFICE.

DAVID MAGGIBBON, OF MANCHESTER, NEW HAMPSHIRE.

BRAIDING MACHINE.

Application filed April 25, 1923. Serial No. 634,585.

This invention relates to braiding machines of the type having an upper and a lower set of braiding carriers which are moved in opposite directions together with means for sinuating the threads from the lower bobbin carrier to cause them to pass over and under the upper bobbin carriers.

One of the objects of the invention is to provide an improved simplified braiding machine which is capable of high speed operation without showing excess wear, and this end is secured by making the machine with relatively few parts and particularly few moving parts. These moving parts may be made relatively light and are all constructed to move in a circular direction. The threads from the lower bobbin carriers are guided at all times in their sinuating movement by an unobstructed and highly polished sinuating guide which passes alternately over and under the upper bobbin carriers.

Another object of the invention is to provide an improved and simplified means for driving the braiding carriers of the upper set.

Still further objects of the invention are to improve generally braiding machines all as will be more fully hereinafter set forth. In order to give an understanding of the invention I have illustrated in the drawings a selected embodiment thereof which will now be described after which the novel features will be pointed out in the appended claims.

Fig. 1 is a plan view of a braiding machine embodying my invention;

Fig. 2 is a partial sectional view;

Fig. 3 is a sectional view taken at the point where one of the sinuating threads is passing underneath one of the upper bobbins.

Fig. 4 is a view of a portion of the rack for driving the upper bobbins.

Fig. 5 is a partial side elevation of the braiding machine.

Fig. 6 is a vertical sectional view with the braiding carriers omitted.

Fig. 7 is a side elevation with the braiding carriers omitted and with parts broken out.

Fig. 8 is a view of the cover plate 54 which covers the gears 22 that are located above the slot 10;

Fig. 9 is a section on the line 9—9, Fig. 5. The bobbins of the upper set are indicated at 1 and those of the lower set at 2. The bobbins 1 of the upper set are supported on braiding carriers 3 which travel in a track 4 formed in a stationary frame indicated generally at 5. The bobbins 2 of the lower set are carried by a rotary turret 6.

The frame 5 is made in two parts and comprises the upper section 7 and the lower section 8, said parts being separated to form a slot or space 10 through which the threads 9 from the lower bobbins pass. The section 7 has an annular formation and the meeting edges of the two sections are shaped so that the space or slot 10 has a sinuous shape illustrated in Figs. 1, 5 and 7, said slot 10 passing alternately above and below the track 4.

The lower section 8 of the frame is provided with a central hub 11 which is secured to a hollow stud 12 that is supported in a base 13. The upper section 7 of the frame is supported on the upper end of a plurality of legs or brackets 14, the latter being secured at their lower ends to the base 13.

The track 4 is formed of a shape to fit the carriers 3 as clearly indicated in Figs. 2 and 3 and a section of the upper wall 55 of the track is removable so as to permit the carriers to be inserted therein as seen in Fig. 6.

The turret 6 which carries the lower set of bobbins is rotatably mounted on the stud 12 and is supported by suitable ball bearings 15. This turret may be driven in any suitable way and is herein shown as having a bevelled gear 16 fast thereon which meshes with and is driven by a bevelled gear 17 on a driving shaft 18, the latter being driven from the driving pulley 19 through a suitable clutch 20.

The braiding carriers 3 supporting the upper bobbins 1 are driven from the turret 6 and for this purpose said turret is provided with an annular rack 21 which meshes with driving gears 22 rotatably mounted on the frame 5, said gears in turn meshing with rack teeth 23 formed on the carriers 3.

The rack teeth 23 are formed on one wall of a V groove in the braiding carriers 3 as clearly shown in Fig. 3 and this groove is so located that the driving point of contact

between the teeth of the gear 22 and the rack teeth 23 comes in the axial line of the bobbins. By thus having the propelling force to which the bobbins are subjected applied thereto in the axial line thereof there is no tendency for the bobbins to twist and a smoother running machine is provided.

Some of the driving gears 22 are carried by the lower section 8 of the frame and others are carried by the upper section 7. All the gears are rotatably mounted on studs 24 and the gears which are carried by the upper section 7 are secured to the portions 25 of said sections which are below the track 4.

The arrangement is such that every third gear is located on the upper section 7. Since all the gears mesh with the rack 21 the rotation of the turret will rotate each of the gears 22 about its stud and these gears mesh with the rack teeth on the carriers 23 the carriers will be driven around the track 4 in an opposite direction to that in which the turret 6 rotates. The space between adjacent gears 22 is slightly less than the length of each carrier 3 so that before any carrier passes out of mesh with one gear it will be carried into mesh with the next adjacent gear and thus the carriers will be continuously driven around the track 4.

The gears 22 are shown as set into recesses 52 formed in the two parts 7 and 8 of the frame and I will preferably cover each gear by a metal cover plate 54 which closes the front of the recesses. The cover plates 54 which cover the gears 22 that are located above the guiding slot 10 are shaped so that the lower edges 58 of said plates form a continuation of the slot 10. The slot 10 is so shaped that as the carriers 3 move around the track 4 in one direction and the turret 6 with its lower bobbin carriers 2 is rotated in the opposite direction the threads 9 leading from the lower bobbins are situated by the slot 10 and are carried alternately over and under the bobbins 1 of the upper set thus producing the braid 26 as usual in braiding machines. The slot 10 may be of uniform width throughout as shown in Fig. 2 or it may have a V formation as shown in Fig. 9. In the latter figure the slot is made wider at its inner face than the outer face and this is the preferable construction, the object of which is to provide a sinuating slot which is free from any obstruction of the passage of the yarn, such for instance as the raised edges of the track guides 4. Furthermore this form of slot allows the yarn 9 to extend straight from the guiding edge of the slot to the braiding point.

The narrow edge of the slot 10 is made smooth and polished so as to afford as little friction as possible to the yarn. Each bobbin 2 of the lower set has associated therewith a spreader arm 57 provided at its end

with a guide eye 33 through which the yarn extends from the lower bobbin and each lower bobbin also has associated therewith a vertically-disposed yarn-guiding finger 28 having a guiding edge 29 over which the yarn passes. This finger 28 is situated as close as possible to the yarn-guiding slot 10 so as to prevent any lagging of the yarn between the two guides. The purpose of the guiding finger 28 is to deflect the yarn between the eye 33 of the spreading arm and the braiding point and to hold the yarn in tension close to the guiding edge of the sinuous slot 10 thus keeping the yarn in time with the movement of the bobbin. The spreading arm is for the purpose of giving a sufficient length of yarn 9 between the eye 33 and the braiding point so that the yarn may have its sinuating movement without materially changing the length of yarn 85 between these points.

In order to prevent the yarn ends 9 from becoming injured in passing between the gears 22 and rack 21 as they pass under the bobbins 1 I have made the rack with notches 27 opposite the points where the yarn ends 9 are delivered so that as each yarn end 9 moves into the lower curve of the slot 10 it will pass into the notch 27 and thus be below the gears 22 as it passes under them. In this way the yarn ends 9 are carried under the gears 22 without contact therewith and without being injured.

Each lower bobbin is provided with some suitable let-off device which controls the tension of the yarn at all times but I make no claim herein to any particular let off construction. The device herein illustrated for this purpose comprises a ratchet 30 rigid with the bobbin and a pivoted spring-pressed pawl 31 adapted to engage the ratchet and having a guide eye 32. The yarn from the bobbin 2 extends directly to the guide eye 32 and thence to the guide eye 33 on the end of the spreader arm 57 and from the eye 33 it extends over the edge 29 of the guiding finger 28, thence through the sinuous guiding slot 10 and then to the braiding point.

35 indicates the take-up drum on which the braid 26 is wound as fast as it is made. This take-up drum may be driven from any suitable source and I have herein shown it as rotated from the shaft 18. This drum is carried by a shaft 36 journaled in up-standing arms 37 and the shaft has fast thereon a gear 38 which meshes with a small gear 39 fast on a shaft 40 that is also journaled in said arms. The shaft 40 is connected by gearing 60 to a sprocket wheel 41 over which passes a sprocket chain 42, the latter being driven by a sprocket wheel 43 fast on a shaft 44. This shaft 44 has a bevel gear 45 thereon meshing with a bevel gear 46 on a shaft 47 and the latter shaft 130

has a worm gear 48 thereon meshing with a worm 49 on the driving shaft 18.

50 indicates a guide through which the braid 26 passes as it is braided, said guide 5 being carried by an arm 51 secured to the up-standing arm 37. This guide 50 not only serves to guide the braid 26 but also serves to control the position of the braiding point.

It will be noted that this machine is designed to stand up under high speed operation and to have certain advantages over other braiding machines of this type. Particularly it has relatively few parts and has no cams or other parts involving difficult machine work in their construction so that the cost of construction is relatively low. The few moving parts may be relatively light and run in a circular direction thus giving very little wear and making very little noise. There is a small amount of friction involved in the operation of the machine and consequently a relatively small amount of power is necessary to operate the machine. The parts are constructed so that they are easy of access and simple to repair.

The combination of the vertical guide 29 and the sinuating guide 10 gives an excellent means for sinuating the yarn from the lower bobbins without the use of mechanical devices.

By the arrangement of gears herein shown wherein every third gear is situated above the guiding groove it is possible to employ three gears only for each two bobbin carriers and, therefore, it is possible to arrange the bobbin carriers closer together than would be the case if it required two gears for each bobbin carrier.

I claim.

1. In a braiding machine, the combination with a frame comprising upper and lower sections and having an annular trackway, of bobbin carriers for the upper bobbins movable in said trackway, said bobbin carriers having rack teeth, a rotatable turret, a set of lower bobbins carried by the turret, the division between the sections of the frame being in the form of a sinuous slot having unbroken walls which form a guide for the yarn from the lower bobbins, said slot passing alternately above and below said trackway, a single annular rack on the turret, intermediate gears journalled in the frame below the trackway, and rotatable about horizontal axes, said gears meshing both with said rack and with the rack teeth on the bobbin carriers, part of said gears being supported by the upper section of the frame and part by the lower section of the frame, said frame sections having recesses in which the gears are received.

2. In a braiding machine, the combination with a frame comprising upper and lower sections and having an annular trackway, of

bobbin carriers for the upper bobbins movable in said trackway, said bobbin carriers having rack teeth, a rotatable turret, a set of lower bobbins carried by the turret, the division between the sections of the frame being in the form of a sinuous slot having unbroken walls which form a guide for the yarn from the lower bobbins, said slot passing alternately above and below said trackway, a single annular rack on the turret, intermediate gears journalled in the frame below the trackway, and rotatable about horizontal axes, said gears meshing both with said rack and with the rack teeth on the bobbin carriers, every third gear being supported by the upper section of the frame and the other gears being supported by the lower section of the frame, said frame sections having recesses in which the gears are received.

3. In a braiding machine, the combination with a two-section frame having on its inner face an annular groove forming a trackway, of bobbin carriers travelling in said trackway and provided with rack teeth, a rotatable turret and lower bobbins carried by the turret, an annular rack on the turret, said frame having recesses in its outer face which communicate with the trackway, gears located in said recesses and journalled in the frame, said gears meshing with said rack and also with the rack teeth of the bobbin carriers, the division between the sections of the frame being in the form of a sinuous slot having unbroken walls which passes alternately above and below the trackway and through which the yarn from the lower bobbins pass, part of the gears being located in the upper section of the frame above the groove, and plates covering said latter gears, the lower edges of the plates extending below the rack on the turret, and forming a continuation of the upper wall of said slot.

4. In a braiding machine, the combination with a two-section frame having on its inner face an annular groove forming a trackway, of bobbin carriers travelling in said trackway and provided with rack teeth, a rotatable turret, lower bobbins carried thereby, an annular rack on the turret, said frame sections having recesses in their outer faces which open into the trackway, gears journalled in said recesses and meshing with the annular rack, said gears projecting into the trackway and meshing with the rack teeth on the bobbin carriers, the division between the sections of the frame being in the form of a sinuous slot through which the yarn from the lower bobbins pass, said slot passing below the gears that are journalled in the upper section of the frame and above the gears journalled in the lower section of the frame, plates covering the gears in the upper section of the frame, the lower edge of said plates conforming in shape to the slot and

functioning as a guide for the lower bobbin threads as they pass under the corresponding gears.

5. In a braiding machine, the combination with a two-section frame having on its inner face an annular groove forming a trackway, of bobbin carriers travelling in said trackway, a rotatable turret, a set of lower bobbins carried thereby, an annular rack on the turret, said rack having yarn-receiving notches, gears journaled on the outside of the frame and meshing with the rack on the turret, said frame having openings through which the gears project into the trackway for meshing with the rack teeth on the bobbin carriers, the division between the sections of the frame constituting a sinuous guide for the yarn from the lower bobbins, part of the gears being journaled in the upper section 20 of the frame above said guide, and plates covering the gears on the upper section, the lower edges of said plates extending below the gears and corresponding in outline to the adjacent portion of said guide and functioning to depress the yarn into the notches of the rack as the yarn passes under said gears.

6. In a braiding machine, the combination with a frame having on its inner face an annular groove constituting a trackway, of bobbin carriers travelling in said trackway, and provided with rack teeth, a rotatable turret, a set of lower bobbins carried by the turret, said frame being divided into upper and lower sections which are separated by a sinuous slot forming a guide for the yarn from the lower bobbins, which slot passes alternately above and below said trackway, a rack on the turret, gears journaled on the frame and meshing with both said rack and the rack teeth of the bobbin carriers, some of said gears being situated above the lower bends of the sinuous guide, said rack having for each lower bobbin a notch extending below the rack teeth and a vertical guiding finger associated with each lower bobbin to guide the yarn into the notch as said yarn passes under the gears above the guiding groove.

- 50 7. In a braiding machine, the combination with a frame having on its inner face an annular groove constituting a trackway, of bobbin carriers travelling in said trackway, and provided with rack teeth, a rotatable turret, a set of lower bobbins carried by the turret, said frame being divided into upper and lower sections which are separated by a sinuous slot forming a guide for the yarn from the lower bobbins, which slot passes alternately above and below said trackway, a rack on the turret, gears journaled on the frame and meshing with both said rack and the rack teeth of the bobbin carriers, some of said gears being situated above the lower bends of the sinuous guide, said rack having

for each lower bobbin a notch extending below the rack teeth, a vertical guiding finger associated with each lower bobbin to guide the yarn into the notch as said yarn passes under the gears above the guiding groove, and a spreading arm extending radially outwardly from the turret adjacent each guiding arm, each guiding finger having an eye at its end through which the yarn from the lower bobbin is led.

75 8. In a braiding machine, the combination with a frame having on its inner face an annular groove forming a trackway, of bobbin carriers travelling in said trackway, a rotatable turret, a rack on the turret, a set of lower bobbins carried by the turret, said frame comprising upper and lower sections separated by a sinuous slot having continuous wall and which forms a guide for the yarn from the lower bobbins, said frame having recesses in its outer face, gears journaled in said recesses and meshing with the rack on the turret, said recesses opening at their upper ends into the trackway so that the upper sides of the gears project into the trackway, the rack teeth on the carriers being situated in a line which intersects the axial line of said carrier, whereby the driving force of the gears is exerted on the bobbin carriers near the axial line thereof.

95 9. In a braiding machine, the combination with a frame having on its inner face an annular groove forming a trackway, of bobbin carriers travelling in said trackway, a rotatable turret, a rack on the turret, a set of lower bobbins carried by the turret, said frame comprising upper and lower sections separated by a sinuous slot having continuous walls and which forms a guide for the yarn from the lower bobbins, said frame having recesses in its outer face, gears journaled in said recesses and meshing with the rack on the turret, said recesses opening at their upper ends into the trackway so that the upper sides of the gears project into the trackway, rack teeth on the carriers facing downwards and situated in a line which intersects the axial line of the carrier, whereby the propelling force is delivered to said carriers in the axial line thereof.

115 10. In a braiding machine, the combination with a two-section frame having on the inner face thereof a groove forming an annular trackway, of bobbin carriers travelling in said trackway, each carrier having rack teeth, a rotatable turret, a rack thereon, a set of lower bobbins carried by the turret, the division between the two sections of the frame being in the form of a sinuous slot having unbroken walls which forms a guide for the yarn from the lower bobbin, said frame having recesses in its outer face, driving gears journaled in said recesses and meshing with said rack, said recesses opening into the trackway so that the driving 120 125 130

gears mesh with the bobbin carriers through said opening, said gears and sinuous guide being so arranged that the guide passes below every third gear and over the other 5 gears.

11. In a braiding machine, the combination with a two-section frame having on the inner face thereof a groove forming an annular trackway, of bobbin carriers travelling in said trackway, each carrier having rack teeth, a rotatable turret, a rack thereon, a set of lower bobbins carried by the turret, the division between the two sections of the frame being in the form of a sinuous slot 10 having unbroken walls which forms a guide for the yarn from the lower bobbins, said frame having recesses in its outer face, driving gears journalled in said recesses and meshing with said rack, said recesses opening into the trackway so that the driving 15 gears mesh with the bobbin carriers through said opening, said gears and sinuous guide being so arranged that the guide passes below every third gear and over the other 20 gears, there being three driving gears for each two upper bobbin carriers.

12. In a braiding machine, the combination with a two-section frame having on its inner face an annular groove forming a 30 trackway, bobbin carriers travelling in said trackway, and having rack teeth, a rotatable turret, a rack thereon, a set of lower bobbins carried by the turret, the division between the sections of the frame constituting a sinuous 35 guide for the yarn from the lower bobbins, horizontally arranged studs carried by the frame, driving gears rotatably mounted on the studs and meshing both with the rack and with the rack teeth on 40 the bobbin carriers, said rack teeth being so located that the driving force of the gears on the rack teeth is exerted on the bobbin carriers at the axial line thereof.

13. In a braiding machine, the combination with a two-section frame having an annular trackway, of bobbin carriers movable in said trackway, a rotatable turret, a set of lower bobbins carried thereby, an annular rack on the turret, gears for driving the 45 bobbin carriers, part of said gears being supported by each frame section, said gears meshing both with said rack and the upper bobbin, the division between the sections of the frame constituting a guiding groove 50 having unbroken walls through which the threads from the lower bobbins pass to the

braiding point, and said groove passing below the gears supported by the upper section of the frame and above the gears supported by the lower section of the frame, all of 60 said gears being situated below and operating on the under side of the bobbin carriers.

14. In a braiding machine, the combination with a two-section frame having an annular trackway, of bobbin carriers movable 65 in said trackway, a rotatable turret, a set of lower bobbins carried thereby, an annular rack on the turret, gears for driving the bobbin carriers, some of the gears being supported on one section of the frame and 70 some on the other section, said gears meshing both with said rack and with the bobbin carriers, the division between the sections of the frame constituting a guiding groove 75 having unbroken walls through which the threads from the lower bobbins pass to the braiding point and said groove passing below the gears supported by the upper section of the frame and above the gears supported by the lower section of the 80 frame, said rack having notches to receive the threads from the lower bobbins as they pass under the gears supported by the upper section of the frame, and vertical guiding fingers secured to the turret and by which 85 the threads are guided into the notches, all of said gears being situated below and operating on the under side of the bobbin carriers.

15. In a braiding machine, the combination with a frame formed in upper and lower sections and having an annular trackway, of bobbin carriers movable in said trackway, a rotatable turret, a lower set of bobbins carried by the turret, driving gears 90 journalled in each section of the frame and meshing with and driving said bobbin carriers, and means to rotate the gears by the rotation of the turret, the division line between the sections of the frame forming a 95 sinuous yarn-guiding groove having unbroken walls for sinuating the yarn from the lower bobbins, which groove passes under each gear journalled in the upper section of the frame and over each two gears 100 journalled in the lower section of the frame, there being only three driving gears for 105 each two bobbin carriers, all of said gears being situated below the bobbin carriers.

In testimony whereof, I have signed my 110 name to this specification.

DAVID MACGIBBON.
